PLAYGROUND CLIMBER

Robert S. Wormser, Hillsdale, Mich., assignor to Game Time, Inc., Litchfield, Mich., a corporation of Michigan

Filed Nov. 26, 1968, Ser. No. 14,682

Term of patent 14 years

Int. Cl. D21—04

U.S. Cl. D34—5

FIG. 1 is an elevational view of a playground climber constituting the design of the invention as taken in the direction indicated by the arrow I of FIG. 4,

FIG. 2 is an elevational view of the playground climber of the invention taken 120° with respect to FIG. 1 in the direction indicated by the arrow II of FIG. 4,

FIG. 3 is an elevational view as taken 120° with respect to FIG. 1 in the direction of the arrow III of FIG. 4, and

FIG. 4 is a top, plan view of a playground climber in the form of a tree in accord with the design of the invention.

I claim:

The ornamental design of a playground climber, substantially as shown and described.
